UNITED STATES PATENT OFFICE.

HENRY HEIDACKER, OF METROPOLIS CITY, ILLINOIS, ASSIGNOR OF ONE-HALF TO LOUIS HENNE, OF SAME PLACE.

COLTER-FASTENING.

SPECIFICATION forming part of Letters Patent No. 340,506, dated April 20, 1886.

Application filed July 29, 1885. Serial No. 172,950. (No model.)

To all whom it may concern:

Be it known that I, HENRY HEIDACKER, a citizen of the United States, residing at Metropolis City, in the county of Massac and State of Illinois, have invented certain new and useful Improvements in Colter-Fastenings, of which the following is a specification, reference being had therein to the accompanying drawings.

10 My invention relates to plow-colters, and has for its object the provision of means whereby a colter may be secured to a plow-beam in such a manner that a strong rearward pressure upon the lower portion of the colter, when the plow 15 is in service, shall not displace it or split or break the plow-beam.

The invention consists in a plate provided upon its face with suitable ribs that embrace the edges of the colter-shank, securing-bolts, 20 and laterally-projecting lugs that engage the upper and lower surfaces of the plow-beam, substantially as hereinafter more fully described, and pointed out in the claim.

In the drawings, Figure 1 represents a portion of a plow-beam provided with my invention. Fig. 2 is a top plan view thereof. Fig. 3 represents a transverse section of the plow-beam, taken on the line $x-x$ of Fig. 2. Fig. 4 represents a detail view of the colter-securing 30 plate detached from the plow-beam. Fig. 5 represents an end view of the plate shown in Fig. 4.

Similar letters of reference in the several drawings denote similar parts.

35 Referring to the drawings, A designates the plow-beam, B the colter, and C a plate by which the colter is secured to the beam. The shank b of the colter B is provided with parallel edges b' , that bear, when said colter is in 40 position upon a plow-beam, against ribs c , cast or otherwise secured to the outer face of the plate C. I preferably form one end of each of the ribs c of greater width than the opposite ends, and place such wider end upon opposite 45 edges of the plate, (see Figs. 1 and 4,) the purpose of which construction will presently be explained.

$c' c'$ designate apertures in the plate C, at diagonally-opposite corners thereof, for the 50 passage of bolts m , whereby the plate is secured

to the plow-beam. $c' c'$ designate similar apertures in said plate, at about the center thereof, for the passage of bolts n , which, in connection with a clip, D, hold the colter in position against the face of the plate between the 55 ribs $c c$.

$C' C'$ designate lugs projecting from the upper and lower edges of the plate at diagonally-opposite corners thereof, as shown.

D designates a clip, which passes from one 60 to the other of the ribs c , and is secured against the face of the colter-shank by bolts n and nuts n' .

The colter B may be adjusted up or down between the ribs $c c$, and held at any desired 65 height by means of the clip D and bolts n .

By reference to Fig. 1 it will be seen that the lugs C' are placed at diagonally-opposite corners of the plate C—one upon the upper forward edge of said plate in front of the colter-shank, and the other upon the lower rear corner 70 of the plate in rear of said colter-shank—and that said lugs extend upon the upper and lower surfaces, respectively, of the plow-beam.

By the above-described construction the 75 plate C is prevented from turning in the direction indicated by the arrows g by force applied in the direction of the arrow o to the lower forward edge of the colter, whereby all danger of breakage or splitting of the beam 80 by plate C turning on the bolts n is obviated, the lugs C' holding the plate from turning, thereby relieving the bolts n from lateral strain, and keeping the colter in its proper position.

The above description has been made in 85 view of the application of my device to a wooden plow-beam; but it will be understood that said plate C may be attached to a metal plow-beam with equally good results, in which case the bolts m may be dispensed with and 90 clips used in lieu thereof to hold the plate in proper position.

To further strengthen the device I preferably make the ribs $c c$ wider at the ends which are adjacent to the lugs C' , thereby increasing 95 the strength of the ribs at points subjected to the greatest strain from the colter.

Modifications of the within-described improvements may be made without departing from the spirit or sacrificing the advantages 100

of my invention—as, for instance, the ribs *c c* may be cut away at the center, and thus admit the clip *D* to bear against the outer surface of a colter-shank, whose thickness is less than 5 the ribs.

What I claim is—

The combination, with the beam and colter of a plow, of the colter attachment, substantially such as herein shown and described, consisting of a plate having lugs at diagonally-opposite corners, which extend over opposite sides of the beam, outwardly-projecting par-

allel and re-enforced ribs, and a clip which overhangs said parallel ribs, said plate and clip having perforations to receive the securing-bolts, whereby the clip is secured to the plate and the plate to the beam, as and for the purpose set forth. 15

In testimony whereof I affix my signature in presence of two witnesses.

HENRY HEIDACKER.

Witnesses:

LOUIS HENNE,
T. J. FUQUA.
